BREAKFRONT WITH DOOR CARVINGS OR THE LIKE

Joseph E. Adkinson, 3807 Leland St.,
Chevy Chase, Md. 20015

Filed Feb. 4, 1972, Ser. No. 223,827

Term of patent 14 years

Int. Cl. D6—04

U.S. Cl. D6—154

FIG. 1

FIG. 2

FIG. 3

FIG. 1 is a view in front elevation of the breakfront with door carvings showing my design.

FIG. 2 is a side elevation of FIG. 1.

FIG. 3 is a top plan view of the breakfront of FIG. 1.

The back of the breakfront is conventionally flat and the side not shown is identical to the side in FIG. 2.

I claim:

The ornamental design for a breakfront with door carvings or the like, substantially as shown and described.
